STRINGED MUSICAL INSTRUMENT

Joe E. Barrick, Cloverdale, Calif.

Application July 26, 1955, Serial No. 37,132

Term of patent 14 years

(Cl. D56—9)

I claim:

The ornamental design for a stringed musical instrument, as shown.
